UNITED STATES PATENT OFFICE.

THOMAS L. WILLSON, OF OTTAWA, ONTARIO, CANADA, ASSIGNOR, BY MESNE ASSIGNMENTS, TO UNITED STATES MARINE SIGNAL COMPANY, OF JERSEY CITY, NEW JERSEY, A CORPORATION OF NEW JERSEY.

SIGNAL-BUOY.

No. 873,917.

Specification of Letters Patent.

Patented Dec. 17, 1907.

Application filed July 26, 1905. Serial No. 271,288.

To all whom it may concern:

Be it known that I, THOMAS L. WILLSON, a subject of the King of Great Britain, residing at Ottawa, Province of Ontario, Canada, have invented certain new and useful Improvements in Signal-Buoys, of which the following is a specification.

This invention aims to provide certain improvements in buoys carrying bells above or below the surface, and preferably also carrying lamps, such for example as in the illuminated or acetylene buoy of my Patent No. 791,119, dated May 30, 1905.

The invention especially provides certain extremely simple but strong and durable mechanism for striking the bell.

Various features of improvement are referred to in detail hereinafter.

The accompanying drawings illustrate a buoy embodying the invention.

Figure 1 is a vertical elevation partly in section through the center of the buoy showing a complete bell-ringing arrangement in elevation; Fig. 2 is a plan of the operating shaft of the bell-ringing mechanism; Fig. 2^a is an edge view thereof; Fig. 3 is a vertical section of the mechanism at the upper end of the shaft; Fig. 4 is a horizontal section on the plane 4—4 of Fig. 3; Fig. 5 is a plan of the same; Fig. 6 is a side elevation of a portion of said mechanism; Fig. 7 is a side elevation of the striker and operating mechanism; Fig. 8 is a part plan and part horizontal section of the same. Figs. 3-8 are views from the opposite side to that of Fig. 1. Figs. 9, 11 and 12 are vertical sections, and Fig. 10 is a horizontal section illustrating modifications.

Referring now to the embodiment illustrated, the buoy is provided with a buoyant body A, and carries a lamp B at the upper part of a superstructure C. A device D for striking the bell is carried below the water level, preferably so far down as to be in the still water, and a bell E is carried by the same superstructure which carries the lamp. The body of the buoy carries also a gas generating chamber F, and appropriate mechanism for regulating the operation and conducting the gas to the lamp, all these being substantially as illustrated in my patent above referred to and requiring no detailed explanation here.

The actuating device D for producing the striking of the bell, is a substantially spiral plate or vane, and is mounted on a vertical

operating shaft G. As the buoy rises and falls, the spiral shape of the vane D produces a turning movement of the shaft back and forth, an irregular oscillation. Likewise as the buoy swings from side to side the vane will be thrown to one side or the other, oscillating the shaft. It will be seen therefore that movement of the buoy in any direction will give a greater or less turn to the shaft. The use of a vertical shaft for transmitting the movement simplifies to the greatest degree the connection between the operating device D and the mechanism for converting its movements into a striking of the bell. The shaft is carried through a tube H in the buoyant body A and close to the central tubular portion J, and is thus exposed only at its lower end to shocks. The oscillating movement being also comparatively slight, the structure is extremely durable.

At the upper end of the shaft G its oscillating movement is converted into a rotary movement, and utilized to operate a striking lever. The mechanism for this purpose is shown as a whole at K (Fig. 1). The details are best shown in Fig. 3. A rotary member L is mounted on the upper end of the shaft intermediate between an upper fixed member M and a lower member N which is keyed on the shaft by a key N'. A ratchet O and pawls P connect the lower and intermediate members, so that when the shaft is rotated in one direction (say clock-wise when looking down upon the top of it), the intermediate member will also be rotated. A second ratchet Q and pawls R form a connection between the intermediate member and the upper fixed member, which prevent the intermediate member from turning backwards, that is to say, anti-clockwise.

The rotary intermediate member L is provided with wings or cams S, which serve to operate the striking lever in the manner hereinafter described. The fixed member M is provided with a flange T at its outer edge surrounding the ratcheted portion of the intermediate member L, and the latter is provided with a similar flange U surrounding the ratcheted portion of the oscillating member O. The parts of this entire mechanism are few and simple, and are protected by the flanges T and U so as to reduce to a minimum the possibility of their getting out of order.

The striker and connected parts are also reduced to the simplest form possible. The

striker is a single heavy lever V, on the end of which is riveted a hammer W, the lever being pivoted on a pin X which depends from a flange at the upper part of the fixed member M on the head of the shaft. A spring is used to force the striker toward the bell until very near thereto, whereupon the momentum of the hammer is depended upon to continue the forward movement until the bell is struck, whereupon the same spring is utilized to withdraw the hammer a short distance to permit the bell to ring freely. Forward and rear stops Y and Z respectively are carried on a rod a which is connected by a link b with the striking lever, and partakes of the forward and backward movements thereof. Forward and rear slides c and d respectively are also carried on said rod a, and are pressed apart against their respective stops by means of a heavy coiled spring e, the slides c and d having flanges enveloping to a great extent the spring e so as to protect it from the weather. The slides c and d fit into a cylinder f bolted to the under side of the flange g of the fixed member M. The rear end h of the cylinder is bolted thereon by means of flanges, as indicated in Fig. 7, and is removable to permit the removal of the spring and slides. The inner face of the cylinder f is provided with longitudinal grooves j which prevent any air resistance to the movement of the slides d, the latter being fitted close to the face of the cylinder so as to have as little play or looseness as possible.

In operation, the wings or cams S carried by the rotary member push forward the short end of the striking lever V and then release the same. When the hammer end of the lever V is pushed backward from its normal position, the rod a carries with it the fixed stop Y and the slide c, pressing the spring against the slide d, which is held from backward movement by the head h of the cylinder, constituting a fixed stop. Upon the release of the lever over the end of the cam, the spring expands and throws the lever forward until the forward slide c strikes against the fixed stop constituted by the forward end of the cylinder, whereupon the momentum of the parts carries the lever still farther forward, drawing forward the fixed stop Z and slide d, and compressing the spring against the front of the cylinder. This movement is sufficient to permit the hammer to strike the bell a good blow, whereupon the compression of the spring is exerted in the opposite direction, and presses the slide d back against the rear head of the cylinder, restoring the parts to their normal position.

The buoy may be weighted at its lower end by any usual or suitable disk k (Fig. 1). Or preferably the counterweight is made as shown in Figs. 9 and 10 of a central ring l, from which extends outward the radial spokes m connected to an outer ring n. The

advantage of this construction is the securing of a considerable weight without seriously interfering with the flow of the water upward or downward upon the spiral vane, and at the same time giving a broad base to stand the buoy on when it is out of the water, and the outer ring N also guides the water against the wing D during the downward motion of the buoy and thereby increases the power available to operate the bell.

The efficiency of the vane, or rather of the water in operating the vane, may be increased by inclosing the same in a tube o preferably open at top and bottom and entirely submerged (Figs. 11 and 12), in which case the vane preferably has two or more wings D D'. This insures a practically unyielding column of water moving upward or downward against the vane, and with much more force than where there is no obstruction at the sides to prevent the water yielding laterally under the pressure.

The tube o is of value not only in connection with the spiral vane shown, but in connection with a variety of other devices for receiving the movement of a column of water. For example, as shown in Fig. 12, the tube may be used with good effect to concentrate the water upon a vertically moving disk p, which nearly fills the tube, and which has a range of movement such as to carry it beyond the open end of the tube to permit the water to escape laterally at the end of the stroke. This disk, as well as the other devices shown, may be applied to the operating mechanism of a bell at any desired location on the buoy.

In connection with other types of buoys than that shown, the vane or disk may be applied in any suitable tubular portion of the buoy.

Though I have described with great particularity of detail certain specific embodiments of the invention, yet it is not to be understood therefrom that the invention is limited to the specific embodiment disclosed. Various modifications thereof in detail and in the arrangement and combination of the parts, may be made within the scope of the appended claims by those skilled in the art, without departure from the invention.

What I claim is:

1. A bell-buoy including in combination a bell, a striker, a spring for forcing said striker toward the bell and a cam for retracting and suddenly releasing said spring, whereby the striker is forced toward the bell, a fixed stop to limit the forward movement of said spring before the striking movement is completed, and a stop carried by the striker and adapted to compress the spring against said fixed stop by the momentum of the striker to permit the completion of the stroke and then retract the striker.

2. A bell-buoy including in combination a

striker, a rod connected thereto, a forward and a rear stop on said rod, a forward and a rear slide, a spring pressing said slides apart against said stops, a forward and a rear fixed stop adapted to be engaged by said forward and rear slide respectively, and means for moving said rod to press said rear slide against its fixed stop and to compress the spring, and then releasing said rod, whereby said spring throws said striker forward till the forward slide strikes the forward fixed stop, whereupon the acquired momentum

carries the rod farther and presses the forward slide against its fixed stop and the spring then restores the parts to their normal positions.

In witness whereof, I have hereunto signed my name in the presence of two subscribing witnesses.

THOMAS L. WILLSON.
